UNITED STATES PATENT OFFICE.

HENRY C. MILLER, OF MILWAUKEE, WISCONSIN.

LOOSE-LEAF BINDER.

1,286,709.

Specification of Letters Patent.

Patented Dec. 3, 1918.

Application filed February 12, 1918. Serial No. 216,758.

To all whom it may concern:

Be it known that I, HENRY C. MILLER, a citizen of the United States, and resident of Milwaukee, in the county of Milwaukee and State of Wisconsin, have invented certain new and useful Improvements in Loose-Leaf Binders; and I do hereby declare that the following is a full, clear, and exact description thereof.

10 My invention consists in improvements in loose leaf binders, the particular object being to provide an arrangement whereby the feed screw for shortening the distance between the binder heads may be held against 15 movement in one direction under normal conditions.

It has been found advisable to provide the better type of loose leaf binders with a quick feed or steep pitch screw shaft whereby the 20 binder heads may be moved apart rapidly with only slight rotation of said shaft. Although this is a very advantageous feature, it is also open to objections inasmuch as the binder heads will tend to move apart 25 slightly after they have been forced against the loose leaves and supposedly adjusted. This invention is primarily designed for overcoming this reaction without interfering with the meritorious features of the 30 quick feed screw.

A further object is to provide an improved means for quickly and easily connecting or disconnecting one end of the binder posts and one of the binder heads.

35 With these general objects and advantages in view the invention resides more particularly in the novel combination, formation and arrangement of parts which will be hereinafter more fully described and 40 pointed out in the claims.

In the accompanying drawings:

Figure 1 represents a vertical longitudinal sectional view through the upper and lower binder heads of a loose leaf binder constructed in accordance with my invention.

45 Fig. 2 is a horizontal section through the lower binder head.

Fig. 3 is a detail transverse section through the lower binder head and taken 50 on the plane of the line 3—3 of Fig. 2, and

Fig. 4 is an inner elevational view, partly in section, of a loose leaf binder having a telescoping back, my invention being applied to the means for extending and 55 tending the back.

The drawings in most of the views illus-

trate structure of usual design such as is shown in my United States Patent Nos. 1,184,979 and 1,236,466, but this construction has been improved upon by the addition of 60 new elements which, although comparatively simple, are very important and add greatly to the efficiency of the binder. This usual mechanism consists of upper and lower binder heads 1 and 2 respectively, flexible 65 extensible binder posts 3 and means for shortening these posts, such means being located within the casing forming the lower binder head 2.

The last mentioned means includes a quick 70 feed or steep pitched screw shaft 4 which extends substantially throughout the length of the binder head 2 and is journaled in bearings 5 carried thereby, and a pair of nuts 6 is disposed on the shaft to be shifted 75 toward and away from each other upon rotation of the latter. The threads of the screw shaft are obviously right and left hand to permit this relative movement between the two nuts. The ends of the binder 80 posts 3 which extend into the binder head 2 are connected to the nuts 6 as shown.

The foregoing elements form no part of the present invention except in so far as they combine with the parts to be herein-after described to produce an operative 85 structure. One of the features of my invention relates to the means for preventing accidental rotation of the shaft 4 in such a direction as to permit the binder head 1 90 to move away from the head 2. This is carried out by reducing one end of the shaft 4 which extends beyond one of the bearings 5 to form a polygonal stud 7, disposing a toothed or ratchet wheel 8 thereon and providing one or more pawls 9 for co-action 95 with the teeth of the same. The wheel is held against rotation on the stud owing to the co-acting relationship between the faces of the latter and the walls of the opening through the former. The portion of said stud which projects beyond the wheel is adapted to be engaged by the socketed end of a key or handle 10 which is projectable through an opening 11 in one end of 105 the binder head 2.

The pawls 9 are pivoted at one end as at 9' so that their free ends extend outwardly and are disposed adjacent the outer end of the stud 7. The outer ends of the pawls are 110 provided with cam faces 12 which are engaged by the inner end of the key 10 as the

same is forced on to the stud 7 as clearly shown in Fig. 2. Such engagement between the faces 12 and the key moves the pawls away from the ratchet teeth and permits 5 ready rotation of the shaft 4.

Upon removal of the key or handle 10 the pawls are forced against the ratchet by means of the springs 13. These springs are preferably V-shaped as shown in Fig. 2, the 10 arms of the same engaging the pawls and the adjacent wall of the binder head. To retain the springs in proper position the free ends of their arms are bent laterally as at 14 and disposed in sockets formed respectively in said pawls and wall of the head 2.

In Fig. 4 the stud 7, the wheel 8, the pawls 9 and the springs 13 are associated with a feed screw shaft 4' which together with links 3' and nuts 6' form operating means 20 for extending or distending the sections A and B of a telescopic back C of a different form of loose leaf binder from that illustrated in the other figures. The pawls 9 are released from the ratchet teeth in the same 25 manner as with the mechanism shown in Figs. 1, 2 and 3.

From the foregoing description it will be seen that the operation of this feature of my invention is comparatively simple, it being only necessary, when a ratchet wheel 8 is used, to insert the key 10 to release the pawls 9. Such release will allow the binder heads to be manually pulled apart, or mechanically moved away from each other by 30 rotation of the key in the proper direction, to release the loose leaves of the binder. The binder heads may be readily forced toward each other by pressing on the uppermost one without the insertion of the key inasmuch 35 as the pawls will ride over the ratchet teeth when the shaft is rotated in one direction. It is evident that an ordinary toothed wheel might be substituted for the ratchet wheel 8 to prevent rotation of the shaft 4 40 in either direction when the pawls 9 are engaged with the teeth of such wheel.

Another feature of my invention is particularly illustrated in Fig. 1, this part relating to means for quickly and easily connecting the ends of the binder posts 3 with the upper binder head 1. This head is hollow, it being preferably formed of sheet metal, and is provided adjacent each end with a pair of openings 15 and 16, said 50 openings being formed in the upper and lower walls respectively and aligned. The holes 15 in the upper wall are sufficiently large to permit a head piece 17 detachably connected with the ends of the binder posts 55 to pass therethrough, while the lower openings 16 are of sufficient size to receive the main portions of the posts, but too small to allow the head pieces to pass therethrough. Thus when the binder posts and the head 1 60 are assembled the head pieces will be posi-

tioned within the latter and engaged with the inner surface of the bottom wall thereof. It is evident from Fig. 1 that in connecting these parts that the head pieces are first removed from the posts and the latter inserted through the openings 15, whereupon the head pieces are again attached thereto. 70

The head pieces 17 are retained within the binder head by means of a plate 18 which slides over the openings 15. This 75 plate extends substantially throughout the length of the binder head and is only slightly shorter than the same to permit the necessary longitudinal movement, which movement is accomplished by shifting a finger 80 piece 19 longitudinally of a slot 20 formed in the upper wall of the binder head. This finger piece is detachably connected with the intermediate portions of the plate 18 as illustrated. 85

When the plate 18 is not in locking position openings 21 adjacent the opposite ends thereof are aligned with the openings 15 to allow the head pieces 17 to readily pass into the binder head. The plate is retained in 90 either of its two positions by the frictional engagement of spring fingers 22 carried thereby with the inner surface of the lower wall of the binder head. Said spring fingers are struck from the plate 18 as shown. 95

With the two improvements hereinbefore enumerated and particularly described added to the binder heads shown in the above mentioned patents, it is obvious that a loose leaf binder of improved construction will result. 100 Furthermore all the additions may be added without any or with only a slight additional cost.

I claim:—

1. A device of the class described comprising a casing, a screw shaft in said casing, one end being reduced to form a polygonal stud, a nut on the shaft, a ratchet wheel disposed on the polygonal stud to rotate with the shaft, a pawl pivoted within the casing to normally engage the teeth of the ratchet, the free end of the pawl having a cam face, a V-shaped spring disposed between the wall of the casing and the pawl, the end of one arm of the spring being 110 engaged with said casing wall and the end of the other arm with one side of the pawl, and a handle having a socket to receive the stud, the end of said handle engaging the cam face of the pawl to move it away from 115 said ratchet teeth. 120

2. A device of the class described including a hollow binder head having a pair of aligned openings through the opposite walls thereof, the opening in one wall being larger 125 than that of the other wall, a binder element disposed through the openings, an enlarged head piece on the end of said element, said head piece being movable through the large opening and engageable with the 130

surface of the other wall within the binder head, and means movable between the head piece and the large opening to retain the former within the binder head.

5. 3. A device of the class described including a hollow binder head having a pair of alined openings through the opposite walls thereof, the opening in one wall being larger than that in the other wall, a binder element disposed through the openings, an enlarged head piece on the end of said element, said head piece being movable through the large opening and engageable with the surface of the other wall within the binder head, and a plate movable over the large opening to close the same and retain the head piece within the binder head.
10. 4. A device of the class described including a hollow binder head having a pair of

alined openings through the opposite walls 20 thereof, the opening in one wall being larger than that in the other wall, a binder element disposed through the openings, an enlarged head piece on the end of said element, said head piece being movable through 25 the large opening and engageable with the surface of the other wall within the binder head, a plate slideable within the binder head to close the large opening and retain the head piece within the former, and a spring 30 tongue struck from the plate to frictionally engage one of the walls of the binder head.

In testimony that I claim the foregoing I have hereunto set my hand at Milwaukee, in the county of Milwaukee, and State of 35 Wisconsin.

HENRY C. MILLER.
